[57] ABSTRACT

Cheeks for use in a printing press web severing device which are made from rubber having a durometer hardness of 65 plus or minus 5. The cheeks are located in knife boxes and are compressed by the web being cut and then expand after the cut has been completed stripping the web from the cutting blade.

3 Claims, 6 Drawing Figures

FIG. 1

FIG. 2

WEB SEVERING DEVICE

BACKGROUND OF THE INVENTION

1. Field of the Invention

Printing press web severing device.

2. Description of the Prior Art

In the printing press rooms of nearly all newspapers there is a very high level of noise whenever the printing presses are being run. This high level of noise contributes to fatigue, loss of hearing and decreases the work performance of each of the persons effected by said noise by a significant amount. This problem is recognized by the trade and much effort has been devoted towards reducing the high level of noise which is present when printing presses are run.

One of the reasons for high noise levels in printing presses is the engagement and disengagement of the cheek woods of the cutting cylinder against the printed webs of paper as said printed webs of paper are cut to sheet lengths.

In the past two cheek woods were utilized, one on each side of the cutting knife inside a cheek block. Usually the cheek woods were made of wood, canvas impregnated with phenolic material or hard plastic. Biasing means (springs) were provided for urging the cheek woods towards the tip of the cutting knife. As the cutting cylinders rotated relative to the mating folding cylinders, the cheek woods were compressed during cutting and the biasing means, after the cutting has been completed, forced the cheek woods in an outward direction. The foregoing movement of the cheek woods and expansion and compression of the biasing means resulted in considerable noise.

Rubber cheeks have been used but with relatively little success inasmuch as the prior art rubber cheeks did not have an adequate work life so that continuous replacement and down time of the printing presses resulted.

SUMMARY OF THE INVENTION

1. Purposes of the Invention

It is an object of the present invention to provide an improved printing press web severing device.

Another object of the present invention is to provide a printing press web severing device which is substantially quieter than the prior art printing press web severing device that utilized cheek woods.

Still another object of the present invention is to provide a printing press web severing device which has a long operating life and increases blade life.

Still another object of the present invention is to provide a printing press having a web severing device that can sever sheets of paper from a web of paper and strip the severed sheets of paper from the cutting blade.

Other objects of the invention, in part, will be obvious and, in part, will be pointed out hereinafter.

2. Brief Description of the Invention

According to the present invention, the foregoing and other objects which will be apparent to those skilled in the art are accomplished by having a printing press which includes a folding cylinder and mating cutting cylinder. The cutting cylinder includes a female opening in which a knife box is located. Said knife box is construed from two pieces which are mirror images of each other. The first piece is bolted to the second piece with a cutting knife being gripped between said pieces and extending outwardly therefrom. A first cheek space is located between said

cutting knife and said first piece and a second cheek space is located between said cutting knife and said second piece. Said first piece includes an overhanging portion as does said second piece.

5 A first cheek made of an elastomer material having a durometer hardness of approximately 65 is provided. The first cheek is L-shaped and includes a base which is substantially rectangular and an extending vertical portion. The overhanging portion of the first piece 10 overlays and contacts a portion of the base of said first cheek. The extension of said first cheek extends past the overhang of said first piece and is adjacent but spaced from, in an inward direction, the tip of the cutting knife blade. A second cheek, identical to said 15 first cheek, is provided and is located in the second space.

Said first and second cheeks flank said cutting knife and are in contact therewith. In addition, there is a slight gap between the extension of said first cheek 20 and said first piece overhang. In a similar fashion, there is a slight gap between the extension of said second cheek and said second piece overhang.

In use, the folding cylinder and cutting cylinder are rotated in unison. A web of paper is passed between 25 said folding cylinder and cutting cylinder. As the two cylinders rotate, the web of paper is forced into the cutting knife which cuts the web. The paper compresses the extension of said first and second cheeks and the bases of said first and second cheeks. As the 30 cutting cylinder rotates, the cutting knife is no longer pointed toward the center of the folding cylinder and the inherent bias of the first and second cheeks causes said first and second cheeks to move outwardly stripping the sheet of paper from the cutting knife. The 35 cycle is then repeated.

The invention accordingly consists in the features of construction, combination of elements and arrangement of parts which will be exemplified in the devices hereinafter described and of which the scope of application will be indicated in the appended claims.

BRIEF DESCRIPTION OF THE DRAWINGS

FIG. 1 is a side plan view of a folding cylinder, 45 cutting cylinder and a portion of a web of paper according to the present invention;

FIG. 2 is a cross sectional view of a folding cylinder and a cutting cylinder having cutting cheeks according to the present invention and a portion of a web of 50 paper;

FIG. 3 is an enlarged sectional view taken substantially along the line 3-3 of FIG. 2;

FIG. 4 is a sectional view of a folding cylinder, 55 cutting cylinder, cheek arrangement and a portion of a web of paper according to a second embodiment of the present invention;

FIG. 5 is a sectional view of a folding cylinder, cutting cylinder, cheek arrangement and a portion of a web of paper according to a third embodiment of the present invention; and

FIG. 6 is a sectional view of a fourth embodiment of the invention.

DESCRIPTION OF THE PREFERRED EMBODIMENTS

In FIGS. 1, 2 and 3 an embodiment 10 of the present invention is shown and includes a folding cylinder 12 and a cutting cylinder 14. Each of said cylinders

is constructed from a conventional case hardened steel (e.g. 4140). Folding cylinder 12 is rotatable about a folding axis 16 and cutting cylinder 14 is rotatable about a cutting axis 18. Cutting cylinder 14 includes a female indentation 20 which extends inwardly from the periphery thereof. Located in indentation 20 is a knife box 22 which is composed of a first knife box piece 24 and a second knife box piece 26. First knife box piece 24 includes a base 28, an upwardly extending side 30 and an overhang 32. A cutting knife 34 is provided which is conventional and includes a cutting edge at the tip thereof. A bolt 36 bolts knife box piece 24 to knife box piece 26 and secures cutting knife 34 in the conventional fashion. A set screw 38 is provided for controlling the radial movement of cutting knife 34.

A rubber cheek 40 having a durometer hardness of 65 plus or minus 5 includes a base 42 and an extended portion 44. Base 42 includes three sides, one of which contacts the left side of cutting knife 34 for the orientation of said cutting knife shown in FIG. 2. The right side of the extension 40 contacts cutting knife 34. The bottom (second) side of base 42 contacts the base 28 and the third side of base 42 contacts the inside surface of upwardly extending side 30. It is to be noted that the shoulder between base 42 and extension 44 contacts the underside of overhang 32 for the unstressed condition of cheek 40. A further point to note is that a slight gap exists between extension 44 of cheek 40 and the radial edge of overhang 32. The outer edge 44a of extension 44 is spaced slightly from the tip of cutting knife 34 in a radially inward direction.

A second cheek 46 is provided which has the same composition as cheek 40 and is the mirror image thereof. Cheek 46 includes a base 48 and an extension 50. Base 48 is in contact with the base of knife box piece 20, in contact with the right side of cutting knife 34 and in contact with the inside vertical surface of knife box piece 26. In addition, the shoulder between base 48 of cheek 46 and extension 50 thereof is in contact with the under surface of the overhang of knife box piece 24. A slight gap exists between extension 50 and the vertical edge of the overhang of knife box piece 26.

A receptacle 12a is located in the periphery of cylinder 12 and received therein is a cutting rubber 12b having notch 12b therein.

In use a web of paper identified by the reference numeral 52 passes between folding cylinder 12 and cutting cylinder 14. The folding and cutting cylinders are rotated in unison and web 52 is passed therebetween and forced into the cutting knife which cuts the web. The paper compresses the extensions of the cheeks. Continued rotation of the cutting cylinder results in the cutting knife being no longer pointed toward the center of the folding cylinder and the inherent bias of the cheeks causes the cheeks to move outwardly stripping the paper from the cutting knife. The cycle is then repeated. Friction between the cheeks and knife blade is at a minimum, minimizing knife blade wear.

The cheek arrangement just described reduces noise and the high frequency sounds that are annoying and cause fatigue. The replacement of the cheeks is simple. Still further, the cheeks help pull the web providing a better looking product. It is very simple to change over from conventional wooden cheeks to

the cheeks of the present invention and this does not require any modifications of existing structure. By using the cheeks of the present invention there is no need for hard woods and/or springs.

5 The cheek arrangement shown in FIG. 2 is particularly suited for a Hoe 3:2 press.

In FIG. 4 of the drawings an alternate embodiment of the present invention 100 is disclosed and is identical to the previous embodiment except as herein-

10 after described. In embodiment 100 the knife box pieces 102 and 104 do not include an overhang.

Cheeks 106 and 108 are provided and are the mirror image of each other and flank cutting knife 110. Cheek 106 is substantially rectangular and is made

15 from a rubber having a durometer hardness of 65 plus or minus 5. Cheek 106 includes a rounded edge 112 which leads to a vertical edge 114 which is spaced slightly from the vertical wall of knife box piece 102.

The base of cheek 106 contacts the base of knife box piece 102 and edge 116 of cheek 106 contacts the left face of cutting blade 110.

Cheek 108 is identically arranged with respect to knife box piece 104 and the right side of cutting blade 108.

25 A pin 118 extends from the vertical portion of knife box piece 102 through a transverse hole in cheek 106, through an enlarged hole 120 in cutting blade 110 and through a hole in cheek 108 to a vertical portion of knife box piece 104. It is noted that registered holes

30 are provided in the vertical portions of knife box pieces 102 and 104 which receive pin 118. It is also noted that hole 120 is substantially larger than the diameter of pin 118 and the inside surface of the holes in the cheeks are in contact with pin 118.

35 By having the upper portions of the cheeks that are spaced from the cutting blade rounded friction is reduced. The pin serves the function of holding the cheeks in place and eliminates the need for the knife box pieces to have an overhang. The operation of 40 the FIG. 4 embodiment is the same as the operation of the previous embodiment.

The structure shown in FIG. 4 is particularly suited for a Goss Mark 1 press.

In FIG. 5 of the drawings an alternate embodiment

45 200 of the present invention is shown and includes knife box pieces 202 and 204 which are identical to the knife box pieces described in connection with FIGS. 1, 2 and 3. Cheeks 206 and 208 are provided which are the mirror image of each other and are made

50 from a rubber having a durometer hardness of 65 plus or minus 5. Cheeks 206 and 208 flank the cutting blade.

Cheek 206 is identical to cheek 40 except as hereinafter described. Cheek 206 includes a rounded

55 upper portion 210 which extends between the upper edge 212 of the cheek to a vertical edge 214 thereof. Vertical edge 214 is spaced slightly from the vertical edge of the overhang of knife box piece 202. Edge 214 extends downwardly to a horizontal edge 216

60 which is spaced below the overhang of knife box piece 202. A gap exists between the vertical section of knife box piece 202 and a vertical edge 218 of cheek 206.

Cheeks 206 and 208 are free floating, i.e. they can 65 move up and down as required. During cutting the cheeks are compressed by the web of paper and after the cutting cylinder is rotated so that the cutting blade is no longer pointed toward the center of the folding

cylinder the cheeks expand stripping the web of paper from the cutting blade. The embodiment shown in FIG. 5 minimizes the amount of friction between the cheeks and the cutting box pieces and provides the advantages heretofore noted. It is noted that the overhang of cutting box piece 202 overlays edge 216 of cheek 206 and prevents the cheek from whirling in an outward direction. A similar arrangement inhibits the radial outward movement of cheek 208.

The structure shown in FIG. 5 is particularly suited for a Goss Mark 2 or Mark 5 press.

In FIG. 6 of the drawings an alternate embodiment of the present invention is shown which is identical to that showing in FIG. 4 except as hereinafter described. In the embodiment on FIG. 6 cheek 300 includes a base 302 and an extended cheek 304. Base 302 includes a bottom 306 and upright sides 308 to 310. Side 308 extends for the full height of the cheek. Side 312 extends inwardly to side 310 to upright side 13. Inclined side 316 extends from side 314 to small flat 318. Small flat 318 is relatively narrow compared to the extension of extended cheek 304. Cheek 320 is identical except being the reverse image of cheek 300.

The structure shown in FIG. 6 is particularly suited for a 3 to 2 or 2 to 1 press.

While all the cheeks can be made from conventional rubber materials it has been found that the use of cheeks made from synthetic rubber, dry filter covering and a sulfur core provide excellent results. As an example, the dry filter covering can comprise 47 percent by weight (plus or minus 10 percent) of the final cheek, the sulfur core 4 percent by weight (plus or minus 5 percent) of the final cheek and the synthetic rubber 9 percent by weight (plus or minus 5 percent) of the final cheek.

Preferably, all cheeks are made as hereinbefore set forth.

While newspaper presses have been shown the structure of the present invention can be used on gravure presses, offsets and any place where sheets of paper are severed.

While one cutting blade has been shown in each embodiment it is to be appreciated that a cutting cylinder may have two cutting blades and utilize the principals of the present invention.

It thus will be seen that there is provided a web severing mechanism which achieves the various objects of the invention and which is well adapted to meet the conditions of practical use.

As various possible embodiments might be made in the embodiment above set forth, it is to be understood that all matter herein described or shown in the accompanying drawings is to be interpreted as illustrative and not in a limiting sense.

I claim.

1. Apparatus for severing a web of paper comprising a cutting cylinder and a folding cylinder, said folding and cutting cylinders being in close proximity to each other with there being a slight clearance therebetween, said cutting cylinder including a female indentation having first and second opposed sides and a base, a knife box mechanism located in said indentation, said knife box mechanism including a first knife box piece and a second knife box piece, said first knife box piece including a side which is flush with a first opposed side of said female indentation,

said first knife box piece further including a base having a bottom surface which is flush with a portion of the base of said female indentation, said first knife box piece further including an overhang extending perpendicularly away from said side thereof towards said second opposed side of said female indentation, said second knife box piece including a side that is flush with said second opposed side of said female indentation, said second knife box piece further including a base having a bottom surface flush with a portion of said female indentation base, said second knife box piece including an overhang which extends perpendicularly away from said side of said second knife box piece, the bases of said first and second knife box pieces being spaced from each other, a bolt extending through said first and second knife box pieces and maintaining said first and second knife box pieces in spaced apart relationship with each other, a first rubber cheek having a base and an extended portion, a shoulder between said base and said extended portion and said first rubber cheek base including an upper surface, said base of said first rubber cheek in contact with said base of said first knife box piece and said side of said first knife box piece, said first rubber cheek base upper surface contacting the overhang of said first knife box piece, a second rubber cheek identical to said first rubber cheek cooperating with said second knife box piece in the same manner that said first rubber cheek cooperates with said first knife box piece, said first and second cheeks being spaced from each other, a cutting knife being located between said first and second rubber cheeks and extending outwardly therefrom and said first and second rubber cheeks having a durometer hardness of 65 plus or minus 5.

2. Apparatus for severing a web of paper comprising a cutting cylinder and a folding cylinder, said folding and cutting cylinders being in close proximity to each other with there being a slight clearance therebetween, said cutting cylinder including a female indentation having first and second opposed sides and a base, a knife box mechanism located in said indentation, said knife box mechanism including a first knife box piece and a second knife box piece, said first knife box piece including a side which is flush with a first opposed side of said female indentation, said first knife box piece further including a base having a bottom surface which is flush with a portion of the base of said female indentation, said first knife box piece further including an overhang extending perpendicularly away from said side thereof towards said second opposed side of said female indentation, said second knife box piece including a side that is flush with said second opposed side of said female indentation, said second knife box piece further including a base which has a bottom surface which is flush with a portion of said female indentation base, said second knife box piece including an overhang which extends perpendicularly away from said side of said second knife box piece, the bases of said first and second knife box pieces being spaced from each other, a bolt extending through said first and second knife box pieces and maintaining said first and second knife box pieces in spaced apart relationship with each other, a first rubber cheek having a base and an extended portion, a shoulder

between said base and said extended portion, said base of said first rubber cheek in contact with said base of said first knife box piece and spaced from said side of said first knife box piece, said first rubber cheek extended portion spaced from the overhang of said first knife box piece, a second rubber cheek identical to said first rubber cheek cooperating with said second knife box piece in the same manner that said first rubber cheek cooperates with said first knife box piece, said first and second cheeks being spaced from each other, a cutting knife being located between said first and second rubber cheeks and extending outwardly therefrom and said first and second rubber cheeks having a durometer hardness of 65 plus or minus 5.

3. Apparatus for severing a web of paper comprising a cutting cylinder and a folding cylinder, said folding and cutting cylinders being in close proximity to each other with there being a slight clearance therebetween, said cutting cylinder including a female indentation having a first and second opposed sides and a base, a knife box mechanism located in said indentation, said knife box mechanism including a first knife box piece and a second knife box piece, said first knife box piece including a side which is flush with a first opposed side of said female indentation, said first knife box piece further including a

base having a bottom surface which is flush with a portion of the base of said female indentation, said second knife box piece including a side that is flush with said second opposed side of said female indentation, said second knife box piece further including a base with said base having a bottom surface flush with a portion of said female indentation base, the bases of said first and second knife box pieces being spaced from each other, a bolt extending through said first and second knife box pieces and maintaining said first and second knife box pieces in spaced apart relationship with each other, a first rubber cheek being substantially rectangular and having a bottom surface and an upright side surface, said bottom surface of said first rubber cheek in contact with said base of said first knife box piece and said upright surface of said first rubber cheek spaced from, parallel to an adjacent said side of said first knife box piece, a second rubber cheek identical to said first rubber cheek cooperating with said second knife box piece in the same manner that said first rubber cheek cooperates with said first knife box piece, said first and second cheeks being spaced from each other, a cutting knife being located between said first and second rubber cheeks and extending outwardly therefrom and said first and second rubber cheeks having a durometer hardness of 65 plus or minus 5.
